UNITED STATES PATENT OFFICE

JOHN WILLIAM WRAY, OF FINCHLEY, LONDON, ENGLAND, ASSIGNOR TO INTERNATIONAL COMBUSTION ENGINEERING CORPORATION, OF NEW YORK, N. Y., A CORPORATION OF DELAWARE

TRAVELING GRATE

Application filed June 19, 1928, Serial No. 286,577, and in Great Britain November 29, 1927.

This invention relates to mechanical stokers of the traveling grate type and particularly to the type of stoker in which the grate bars are supported by means of an endless carrying chain.

It is the primary object of my present invention to provide a stoker of the type referred to wherein the removal of individual grate bars may be easily and quickly effected when desired.

It is a further object of my invention to provide a structure wherein the provisions made for removal of the grate bars are such that the danger of accidental removal, as by dropping, during operation of the stoker is practically obviated.

A further object is the provision of a stoker in which the individual grate bars may be easily removed therefrom at any point when the stoker is at rest, or, stated in another way, without the necessity of moving the stoker to a certain position in order to remove a particular bar. This latter feature has been difficult to achieve heretofore without incurring the danger that the bar may be accidentally removed during operation of the stoker, and this difficulty has been overcome by my invention.

These, together with such other objects as may hereinafter appear, or are incident to my invention, I obtain by means of a construction which I have illustrated in preferred form in the accompanying drawings, wherein—

Fig. 1 is a cross section through a portion of a stoker of the type referred to, and is taken substantially on the line 1—1 of Fig. 2, showing the grate bars in elevation for the sake of clarity.

Fig. 2 is a section taken substantially on the line 2—2 of Fig. 1 with the grate bars in the plane of the section removed.

Fig. 3 is a view similar to Fig. 1 illustrating a modification, and

Fig. 4 is an isometric view of the grate bar carrier shown in Figs. 1 and 2.

As an illustration of the general type of stokers to which my invention is applicable, reference is made to Patent No. 1,649,557, issued November 15, 1927.

Referring to Figs. 1 and 2, the stoker comprises a plurality of parallel endless chains each of which is made up of a plurality of supporting links 5 connected by short links 6. The links 5 carry spindles 7 which are encircled by the sleeve 8 which extend between adjacent chains. Rollers 9 which are secured to the sleeves 8 travel over revolving drums (not shown) at each end of the stoker and over suitable intermediate supports (not shown) in a known manner, and the grate is thus supported in operation.

Grate bar carriers 10—11 are also secured to the supporting links 5 by means of bolts 12, and a group of grate bars 13 is supported at one end in each carrier 10 and at the other end by a corresponding carrier 11 on the next chain.

The carriers 10 and 11 (see Fig. 4) have downwardly projecting lug portions 14 which fit between sections of the link 10 and are secured thereto by means of bolts 12 which pass through bolt holes 15.

Each carrier 10 also has a number of holes 16 which extend through it and provide bearings in the carrier for the trunnions 17 of the grate bars 13. The upper portion of each carrier 10 is also provided on each side with slots 18 which open into the upper part of the holes 16 for a purpose to be hereinafter described.

From the above it will be seen that the trunnions 17 form a pivotal support for the grate bars 13 which are free to turn. The grate bars 13 also have a projecting shoulder 19 at each end which engages the carriers 10 and 11, respectively, and thus limits the turning movement of the grate bar with reference to the carrier to an arc of about 90°.

That portion of the grate bars which lies between the shoulders 19 and the trunnions 17 comprises an upper shoulder 20 (see Fig. 2) and thinner web portion 21. The shoulder 20 is of the same thickness as adjacent portions of the grate bar and is wider than the slots 18 in the carrier 10, but the web 21 is slightly thinner than the width of the slots 18 and extends upward from the trunnion to a point just above the top of the carrier 10.

when the grate bar is at substantially right angles to the carrier.

With the grate bar in this position, it will be seen that the web 21 of a bar will register with the slot 18 of the carrier.

In order to remove one of the bars 13, the adjacent bars which are carried in the opposite side of the carrier 10 (those to the left in Fig. 1, for example) are placed in the position shown in Fig. 2 in order to permit the shoulder 19 of the bar which is to be removed to clear the shoulders of the others. The bar which is to be removed is then turned to a position at right angles to the carrier so that the web 21 will register with and enter the slot 18 and the bar is then slid toward the carrier 10. The depth of the slot 18 is sufficient to permit the bar 13 to be moved enough to allow the trunnion 17 on the opposite end thereof to clear the carrier 11. The grate bar is then tilted up until the bottom will clear the carrier 11 and then the trunnion 17 may be slid out of the carrier 10 and the bar removed. The central bar in Fig. 1 is shown in a position with the web in the slot at the left and the trunnion 17 at the right clear of the carrier 11. The trunnion of the grate bar fits loosely into the slotted carrier in order to permit of the tilting described.

The normal space between abutting trunnions is, of course, sufficient to allow any bar to be removed.

At this point it should also be noted that it is only necessary to provide alternate chains with carriers 10, carriers 11, without slots, being used on the other chains.

The shoulder 20 of each bar will engage the carrier to prevent lateral movement of the bar, except when it is at substantially right angles to the carrier. The bar is in such position relative to the carrier, in normal operation only at such times (i. e., when passing over a drum) as it is in movement in turning from one position to another, and it is extremely unlikely that the web would enter the slot when the bar is turning. Furthermore, the shoulders 19 of the bars normally abut the shoulders of the bars carried in the opposite side of the same carrier, and this also prevents any undesired lateral movement.

In the construction illustrated in Fig. 3, the parts are the same as in the other construction, with the exception of the grate bar 13' and carrier 10'.

In Fig. 3 it is the grate bar which is slotted as at 22 and the carrier 10' has no slots. The removal of the bar is effected just as in the construction of Figs. 1 and 2.

It will be seen from the above that there is no necessity of moving the stoker to any particular position to effect a removal of any bar and that the bars may be removed and

replaced quickly and without the use of special tools.

I claim:—

1. A traveling grate construction including a plurality of grate bar carriers, removable grate bars pivotally supported by the said carriers and slots in one of the carriers, the grate bars having web portions which are thin enough to enter the slots to permit lateral movement of the grate bars toward such carrier. 70 75

2. A traveling grate construction including a plurality of grate bar carriers, removable grate bars extending between and pivotally supported in said carriers, slots in one of the carriers, the grate bars having web portions which are thin enough to enter said slots to permit lateral movement of the grate bars toward such carrier, and shoulders on the grate bars which normally engage the said carrier to prevent lateral movement of said bars. 80 85

3. A traveling grate construction including a plurality of removable grate bar members which are pivotally mounted at each end in a carrier member, a slot in one of said members into which the other may enter when the members are in predetermined angular relation, and means preventing such entering when the members are in any other angular relation. 90 95

4. A traveling grate construction including a plurality of removable grate bar members which are pivotally mounted at each end in a carrier member, a slot in one of said members into which the other may enter when the members are in predetermined angular relation, and a shoulder on one of said members which engages the other member to prevent such entering when the members are in any other angular relation. 100 105

5. A traveling grate construction including a plurality of removable grate bar members which are pivotally mounted at each end in a carrier member, a slot in one of said members into which the other may enter when the members are in predetermined angular relation whereby the grate bar may be moved laterally a sufficient distance to disengage the opposite end of the bar from its carrier. 110 115

6. A traveling grate construction including a plurality of removable grate bar members, a carrier member for each end of the said grate bar members, each carrier member having an opening into which the bar is pivoted, a slot in one of said members into which the other may enter when the members are in predetermined angular relation whereby the grate bar may be moved laterally a sufficient distance to disengage the opposite end of the bar from its carrier, the opening in the other carrier being sufficiently large to permit tilting of the bar when so disengaged. 120 125 130

7. A traveling grate construction including a plurality of groups of removable grate bar members which are pivotally mounted end to end in grate bar carriers and which 5 may be moved laterally when in a certain predetermined relation with a carrier, and shoulders on said bars which abut with the bars of an adjacent group to prevent lateral movement thereof when the bars lie in substantially the same plane.

10 8. A traveling grate construction including a plurality of groups of removable grate bar members which are pivotally mounted end to end in grate bar carriers and which 15 may be moved laterally when in a certain predetermined relation with a carrier, and shoulders on said bars which normally abut bars of an adjacent group to prevent lateral movement thereof, the bars of one group being 20 movable to permit lateral movement of any bar of an adjacent group.

25 9. A traveling grate construction including a plurality of groups of removable grate bar members which are pivotally mounted end to end in grate bar carriers and which 30 may be moved laterally when in a certain predetermined relation with a carrier, the ends of the bars of one group normally abutting ends of bars of an adjacent group to prevent lateral movement thereof, the bars of one group being movable to permit lateral movement of any bar of an adjacent group.

35 In testimony whereof I have hereunto signed my name.

JOHN WILLIAM WRAY.
